UNITED STATES PATENT OFFICE.

EMERY J. WILSON, OF CLEVELAND, OHIO.

HOISTING AND CONVEYING APPARATUS.

1,267,727.

Specification of Letters Patent. Patented May 28, 1918.

Application filed August 9, 1915. Serial No. 44,499.

To all whom it may concern:

Be it known that EMERY J. WILSON, citizen of the United States, residing at Cleveland, in the county of Cuyahoga and State of Ohio, has invented certain new and useful Improvements in Hoisting and Conveying Apparatus, of which the following is a specification.

This invention relates to improvements in hoisting and conveying apparatus generally, and particularly to locomotive crane construction.

More specifically the invention relates to a locomotive crane comprising suitable track wheels and axles, a truck supported upon said axles, a bed mounted upon the truck and adapted to revolve thereon, a boom supported on the bed and adapted to be raised and lowered, suitable drum mechanisms for raising and lowering the boom, and for raising and lowering the load, and suitable operating mechanism connected to any suitable source of power and arranged in a manner such that the power for propelling the crane in either direction, and for swinging the boom, or in other words, revolving the bed, in either direction is transmitted from a single prime shaft. The power for driving the load and boom hoist drums may also be transmitted from the said prime shaft, or it may be obtained from an independent source.

The invention may be further briefly summarized as consisting in the construction and combination of parts hereinafter set forth in the following description, drawings and claims.

Referring to the drawings, Figure 1 is a top plan view with parts broken away, showing the main operating mechanism of the crane; Fig. 2 is a vertical section on the line A—A of Fig. 1; Fig. 3 is a section through the center line of the prime shaft; Fig. 4 is a section through the center line of the drum shaft; Fig. 5 is a section on line M—M of Fig. 4, showing the arrangement of clutch mechanism for operating the load and boom hoist drums; Fig. 6 is a section on line N—N of Fig. 5, showing further detail of the clutch mechanism; Fig. 7 is a section on the line P—P of Fig. 4, showing arrangement of brake mechanism for controlling the load and boom hoist drums; Fig. 8 is a side elevation of the entire crane; Fig. 9 is a plan view of one of the clutches on the prime shaft with a part of the drum broken away;

Fig. 10 is a section on line R—R of Fig. 9 with sliding collar 47 omitted; Fig. 11 is a section on the line S—S of Fig. 10; Fig. 12 is a section on the line T—T of Fig. 10, looking to the right; and Fig. 13 is a section on the line T—T of Fig. 10, looking to the left.

In carrying out the invention any preferred form of construction of parts may be employed so long as they possess the necessary characteristics, but I have shown one arrangement which is effective, and in this embodiment 1 represents the supporting wheels which are arranged in the usual manner upon axles 2. Each of these axles is provided with a bevel gear 3 which meshes with a bevel pinion 4 mounted upon a longitudinally disposed shaft 5 supported in bearings 6 secured to the underside of the truck frame 7. Near the center of the truck the shaft 5 is provided with a driving gear 8 meshing with a pinion 9 carried by a shaft 10 supported in a bushing 11 arranged in the framework of the truck. Shaft 10 carries at its upper end a gear 12 utilized in propelling the crane along the track, and this gear receives power in a manner to be described.

Pivoted upon the bushing 11 is a main bed 13. This bed is provided with suitable rollers 14 engaging a track or other way 15 arranged upon the truck frame. The circular track 15 is provided internally with teeth 16 adapted to mesh with a pinion 17 mounted upon a shaft 18 carried by a bearing 19 forming part of the bed. The upper end of this shaft is provided with a bevel gear 20 meshing with a driving pinion 21 supported upon a shaft 22 mounted in bearings 23 projecting upward from the bed. The forward end of this shaft 22 is provided with a main driving bevel gear 24 receiving power in a manner to be described.

Projecting upward from the main bed 13 are two side frames 25 provided with bearings for supporting a main power shaft 26, a drum shaft 27 and the boom heel pins 28. Power shaft 26 may be driven through the usual connections from a steam engine, internal combustion engine, electric motor, or any other desirable prime mover. An A-frame structure consisting of two posts 29, one on either side, with tie rods 30 securely anchored to the bed 13, serves to support the head end of the boom 31 by means of a rope 32 which is reeved back and forth over

sheaves 33 supported on a transverse pin 34 at the peak of the A-frame, and sheaves 35 secured to the boom head pin 36 by links 37. The rope 32 has one end secured to the links at 38 while the other end is secured to a winding drum 39 mounted on shaft 27, so that when the drum is rotated in a direction to wind or unwind the rope, the head end of the boom is raised or lowered respectively.

From a winding drum 40 on shaft 27 a load hoist rope 41 runs over a sheave 42 mounted on pin 36 and carries a hook 43 or other suitable means for supporting the load 44.

The main drum shaft 27 carries the winding drums 39 and 40 and gears 45, both drums and gears being free to turn on said shaft. The drums are each provided with friction flanges 46 adapted to receive brake bands 47 and clutch bands 48. The gear 45 is driven by a pinion 49 keyed on the power shaft 26, and in turn drives its respective drum by a clutch mechanism comprising the band 48 which is carried by the gear and adapted to be tightened about the friction flange 46 thereby applying a clutching action between the driving gear and winding drum.

Referring to Figs. 5, 6, and 7, the dead end of the clutch band 48 is anchored to a pin 50 carried by the gear 45, and the live end is connected through a right and left adjusting nut 51 to the arm 52 of a rocker 53 having a fixed pivot pin 54 held in the gear member. The rocker 53 is operatively connected to a sliding sleeve 55, Fig. 4, by a universal-joint linkage 56, levers 57 and 58 keyed to the shaft 59, and links 60, Fig. 4. The shaft 59 has bearings 61 in the gear member. The sleeve 55 is mounted on the extended hub of the gear 45 and may be moved in and out along the axis of the shaft by any of the various means common in practice.

From the construction it is seen that a motion of the sleeve inward, *i. e.*, away from the side bearing 25, results in a clockwise rotation of the rocker 53, thereby tightening the band and applying its clutching action; while a motion of the sleeve outward results in a positive release of the clutch.

Brake bands 47 are provided for sustaining or lowering the loads when the clutches 48 are released. Referring to Fig. 7, the dead end of the band is anchored at 62 to the rotating bed structure 13 and the live end is connected through the right and left adjusting nut 63 to one arm of a bell-crank lever 64 having a fixed fulcrum at 65 in the bed 13. A foot pad 66 connected at 67 to the other arm of the bell crank is utilized for operating the brake, a motion downward of the pad resulting in tightening the band and applying the brake in a well known manner.

The power shaft 26 carries keyed to it the

driving pinions 49 meshing with the gears 45, and the clutch driving sleeves 68, 69 and 70. Loosely mounted upon the shaft are the clutch driven bevel gears 71, 72, 73 and 74, each of which carries a clutch drum 75 adapted to receive a clutch mechanism comprising an internal expanding band carried by the driving sleeves.

Inasmuch as these four clutch mechanisms are similar in construction and operation a description of one will suffice for all and this description will be confined to the clutch mechanism between the driving sleeve 68 and the bevel gear 73.

Referring to Figs. 9, 10, 11, 12 and 13, the driving sleeve 68 is secured to the shaft 26 by a key 76 and is provided with a radial web 77 carrying a peripheral flange 78 within but less in diameter than the drum 75, and forming a support for a clutch band which is made up of band portions 79 and 80, each portion being provided at its lower end, as shown in Fig. 10, with an ear 81, the two ears receiving a right and left hand adjusting screw 82. These half band portions are held in place by plates 83 secured to the sides of the flange 78. Friction linings 84 are secured to the band portions and are adapted to engage with the inner cylindrical friction surface of the drum 75. These band portions, united by the adjusting screw 82, form a continuous band, the free ends of which, as shown in Fig. 10, are each provided with an inwardly extending lug 85, the right hand end being anchored in a recess 86 formed in the driving sleeve web 77, as shown by dotted lines in Fig. 10, while the opposite end engages in a recess 87 formed in the end of a lever 88, which is pivoted upon a pin 89 secured in the web 77 at a point substantially diametrically opposite to the socket 87. This lever extends beyond the pivot 89 and is provided with a counterweight 90 and a release spring structure comprising an eye 91 engaging a pin 92, secured to the end of the lever, a spring seat 93 forming a part of the eye and receiving the thrust of a compression spring 94 arranged upon a threaded rod 95 provided with an eye 96 engaging a pin 97 secured in the web 77. An adjusting nut 98 serves as a means for varying the compression of the spring. The web 77 is provided at a point near the dead end recess 86 with a friction roller pocket 99 adapted to receive a friction roller 100 mounted on a pin 101 shown in full lines in Fig. 9 and in dotted lines in Figs. 10 and 12. Opposed to this roller and arranged in the end of the lever 88 adjacent to the recess 87 is another friction roller pocket 102 adapted to receive a friction roller 103 mounted upon a pin 104, shown in dotted lines in Figs. 9 and 10. The rollers 100 and 103 are opposed to each other and adapted to engage on opposite sides of a wedge 105 which is secured to the sliding

collar 106. The pocket end of the lever 88 is provided with a pair of ears 107 and 108, which receive a tongue 109 formed on the sleeve flange 78, and serve to hold the lever 5 in proper alinement.

From the foregoing it will be seen that when the wedge is withdrawn from between the rollers the spring 94 will move the lever 88 in a clockwise direction and contract the 10 band upon the flange 78, when the clutch mechanism will be free to rotate without driving the drum 75. When the wedge is inserted between the rollers the band is expanded in a well known manner and the 15 drive is transmitted to the drum.

Referring to Figs. 3 and 12, the sliding collar 106 carries two wedges 105 and 110 adapted to operate the inside pair of clutches which drive the gears 73 and 74 as the collar 20 is shifted to the left or right respectively of its central position by means of the forked lever 111 fulcrumed at 112. The sliding collars 113 and 114 each carry a single wedge and are adapted to operate the 25 outside pair of clutches which drive the gears 71 and 72 respectively. These two collars are operatively connected by forked levers 115 and 116, fulcrumed at 117 and 118, and link 119, so that they are constrained to move in unison and in the same 30 direction. When the sliding collars are in their central positions as shown in Fig. 3, the clutches are all released and the gears 71, 72, 73, and 74 are free to turn upon the 35 shaft. A movement of the collars to the right or left results in driving one gear of the pair while the other remains free to turn upon the shaft.

The power shaft is in alinement both with 40 the vertical propelling shaft 10 and with the horizontal rotating shaft 22. The outside pair of bevel gears 71 and 72 are in mesh with the bevel gear 12 which drives the propelling mechanism, while the inside pair of 45 bevel gears 73 and 74 are in mesh with the bevel gear 24 which drives the rotating mechanism.

From the foregoing description it will be seen that the following operations can be 50 performed when the power shaft 26 is driven in one direction of rotation. The crane can be propelled along the track in either direction by engaging the proper clutch bevel gear 71 and 72. The bed can be rotated in 55 either direction by engaging the proper clutch bevel gear 73 and 74. The load can be hoisted or lowered by means of the clutch and brake bands which engage the winding drum 40. The boom can be raised and lowered 60 by means of the clutch and brake bands which engage the winding drum 39. It is further to be noted that all of the above operations are independent of each other.

The particular feature of the construction 65 to which this invention relates is the novel

arrangement of the mechanism mounted on the power shaft 26. The gears 71 and 72 with their clutch mechanisms compose one independent reverse driving unit adapted to convey direct and reverse rotary motion to the 70 wheels supporting the truck, while the gears 73 and 74 with their clutch mechanisms compose a second independent reverse driving unit adapted to convey direct and reverse rotary motion to the bed. Other features 75 of the construction are relevant only in so far as they enter into the several combinations as set forth in the following claims.

Having described my invention, I claim:

1. In a hoisting and conveying apparatus, 80 a truck, wheels for said truck, a rotatable bed mounted on said truck, a driving shaft, and two pairs of driving members mounted on said shaft, one pair for transmitting direct and reverse motion to the truck wheels 85 and the other pair for transmitting direct and reverse motion to the bed, the members of one of said pairs lying between the members of the other pair.

2. In a hoisting and conveying apparatus, 90 a truck, wheels for said truck, a rotatable bed mounted on said truck, a horizontal driving shaft, two pairs of beveled gears mounted on said shaft, the gears of one pair lying between the gears of the other pair, a 95 horizontal shaft connected to rotate said bed and provided with a beveled gear co-operating with the gears of the inner pair for transmitting direct and reverse motion to the bed, and a vertical shaft connected to 100 the truck wheels and provided with a beveled gear co-operating with the gears of the outer pair for transmitting direct and reverse motion to the truck wheels.

3. In a hoisting and conveying apparatus 105 a truck, wheels for said truck, a rotatable bed mounted on said truck, a horizontal driving shaft, two pairs of beveled gears mounted on said shaft, the gears of one pair lying between the gears of the other pair, a 110 horizontal shaft connected to rotate said bed and provided with a beveled gear co-operating with the gears of the inner pair for transmitting direct and reverse motion to the bed, a vertical shaft connected to the 115 truck wheels and provided with a beveled gear co-operating with the gears of the outer pair for transmitting direct and reverse motion to the truck wheels, a clutch on said driving shaft between the gears of the inner pair for selectively connecting either one thereof to said shaft, and two clutches on 120 said shaft and co-operating with the outer faces of the gears of the outer pair for selectively connecting either one thereof to 125 said shaft.

4. In a hoisting and conveying apparatus, 130 a truck, wheels for said truck, a rotatable bed mounted on said truck, a driving shaft, two pairs of driving members mounted on

said shaft, one pair for transmitting direct and reverse motion to the truck wheels and the other pair for transmitting direct and reverse motion to the bed, the members of 5 one of said pairs lying between the members of the other pair, a clutch between the members of the inner pair for connecting either one thereof to said shaft, and clutch members on the outer faces of the outer driving

members for connecting either one thereof 10 to said shaft.

In testimony whereof I affix my signature in presence of two witnesses as follows:

EMERY J. WILSON.

Witnesses:

G. O. FARQUHARSON,
D. TOZER.
